PNEUMATIC DROP HAMMER

Reginald P. Fitzgerald, Braintree, Mass., assignor
to Pneumatic Drop Hammer Company, Braintree, Mass., a corporation of Massachusetts

Application March 3, 1948, Serial No. 12,707

10 Claims. (Cl. 121—30)

1

This invention relates to improvements in pneumatic drop hammers and the principal object of the invention is to provide a pneumatic drop hammer of economical construction in which the operation of the hammer is controlled by a single valve having manually operable means for controlling the force of the blow of the hammer.

More specifically the object of the invention is to provide a pneumatic drop hammer having a lifting cylinder and piston connected to the hammer with means for supplying air under pressure to the lifting cylinder and manually operated means for so regulating the escape of air from the cylinder to permit the hammer to drop at a controllable speed and thereby to adjust the force of impact of each blow.

A further object of the invention is to provide manually operable means for so adjusting the controlling means as to cause the hammer to strike successive blows of the hammer with the same force of impact.

Another object of the invention is to provide a pneumatic drop hammer construction of the character described with means for automatically preventing any possibility of the hammer striking an undesirable repeat blow.

A further object of the invention is to provide a novel mechanism for cushioning and arresting the upward movement of the hammer.

Another important object of the invention is to provide manually operable means for actuating the controlling means which will prevent undesirable shock or injury to the operator.

Another object of the invention is to provide a standard for a drop hammer so constructed as to enable the operator to sit while operating the hammer in a position directly facing the hammer and anvil thereby facilitating feeding blanks to the anvil and more easily and conveniently controlling the operation of the hammer.

Another object of the invention is to provide a drop hammer construction having a single rotatable operating valve with an axially aligned control rod connected thereto by a universal joint thereby to prevent binding or wear of the valve in its bearing.

These and other objects and features of the invention will appear more fully from the following description and the accompanying drawings and will be particularly pointed out in the claims.

A preferred embodiment of the invention is illustrated in the accompanying drawings, in which,

Fig. 1 is a front view of the drop hammer;

2

Fig. 2 is an enlarged detail view, partially in vertical section, illustrating the control valve and the mechanism for actuating the same;

Fig. 3 is a detail horizontal sectional view on line 3—3, Fig. 2;

Fig. 4 is a detail horizontal sectional view on line 4—4, Fig. 2;

Fig. 5 is a horizontal sectional view on line 5—5, Fig. 2;

Fig. 6 is a detail horizontal sectional view on line 6—6, Fig. 2;

Fig. 7 is an exploded detail view of the mechanisms for mounting the lower end of the control rod and the means for adjusting the same so to limit the rotative movement of the valve as to restrict the rate of escape of air from the cylinder to produce a blow of the hammer of predetermined force;

Fig. 8 is a detail view mainly in vertical section of the lower portion of the lifting cylinder, the piston and piston rod therein, and the buffer construction for cushioning and arresting the upward movement of the hammer;

Fig. 9 is an exploded view illustrating the universal connection between the valve stem and the valve operating rod shown in Fig. 2; and,

Fig. 10 is a horizontal sectional view of the base of the hammer on line 10—10, Fig. 1.

The drop hammer shown in the accompanying drawings comprises an integral cast metal base in the form of a pedestal having a rectangular bottom section 1, an intermediate section 2 of upwardly converging cruciform cross section having vertical ribs 3 extending at right angles to each other and a rectangular flat upper section 4 of suitable area and thickness forming an anvil upon which is mounted the usual die shoe 5 and the superstructure of the hammer and the operating mechanisms therefor.

This pedestal construction is adapted to permit the legs of an operator, when seated, to straddle the forwardly extending rib and thus comfortably to face the operating parts of the machine and the controlling mechanisms therefor and conveniently to place blanks upon the die and to operate the controlling mechanism.

The means for supporting and actuating the hammer include a frame which is mounted upon the anvil having vertical preferably cylindrical columns 6 and 7 forming guides for a hammer 8. The upper ends of the columns 6 and 7 extend through and are mounted in an overhead beam 9 and base members 10, which connect the beam 9 to the anvil, are located rearwardly of the columns 6 and 7 respectively.

The overhead beam 9 has centrally of its length a vertical aperture 11, as shown in Fig. 8, which constitutes the cylinder of a dash pot for cushioning and arresting the upward movement of the hammer.

A hammer-lifting cylinder 12, of greater diameter than said aperture, is mounted on the beam 9 in axial alinement with the aperture 11 therein. A piston 13, which slidably fits the cylinder 12, has a vertical piston rod 14, the lower end of which is secured to the hammer 8. A collar 15, which is fixedly secured to the cylinder 12 and is bolted to the upper face of the beam, has an internal rabbet in its lower face which encloses the periphery of a rigid annular plate 16 which forms a common head for the lifting cylinder 12 and the cylinder 11 of the buffer and has an upwardly extending circular wall 17 surrounding and narrowly spaced from the piston rod to permit air under pressure to pass from the lifting cylinder 12 into the buffer cylinder 11. Preferably a reinforcing washer 18 which surrounds the wall 17 extends into the rabbet and is clamped therein by the collar 15.

The cylindrical aperture 11, which forms the cylinder of a buffer for cushioning and arresting the upward movement of the hammer, is provided with a piston 19 having an annular gasket 20 of U-shaped cross section secured to its upper face, engages the piston rod and the cylinder wall. The piston 19 has an integral downwardly extending tubular sleeve 21 slidably fitting the piston rod 14 and extending through the lower head of the buffer cylinder 11 which, as shown, is a heavy metal plate 22 which is secured to the lower face of the beam 9. However, it will be understood that the lower head of the buffer cylinder may be an integral web of the beam if the cylindrical aperture and a central opening therein is bored downwardly into but not completely through the beam 9. Suitably controlled means are provided for supplying air under pressure to the lifting and buffer cylinders to raise the hammer and to cushion and arrest the upward movement thereof. In the preferred embodiment of the invention shown herein the overhead beam is provided with a longitudinal bore 23 forming a conduit having an upwardly extending section 24 communicating with an L-shaped bore 25 in the collar 15 to communicate with an alined aperture in the cylinder sufficiently near the lower end thereof to enable air under pressure when exhausted from the cylinder to discharge any lubricating oil which accumulates upon the plate 16 between its upwardly extending central wall 17 and the wall of the cylinder.

The piston rod 14 has adjustably secured to it a collar 26 adapted to be so positioned as properly to engage the sleeve 21 when the hammer approaches the upward limit of its movement thereby raising the piston 19 against the force of the air under pressure supplied to the lifting and buffer cylinders thereby to cushion and arrest the movement of the piston. Upon exhaust of air from the lifting cylinder the buffer piston and its sleeve 21 will descend until the piston rests upon the lower head 22 of the buffer cylinder.

One of the important objects of the invention is to provide means for so controllably regulating the exhaust of air from the cylinder as to cause the hammer to strike a blow of maximum force, or a blow of predetermined force less than the maximum, or selectively to strike a plurality of blows of uniform predetermined force.

In the present construction the conduit 23 in the overhead beam communicates at its end remote from the cylinder with the atmosphere or with a suitable muffler 27 as shown in Fig. 1 and 5 a single operating valve in the conduit 23 controls the admission of air to the lifting and buffer cylinders and the rate of exhaust of air from the lifting cylinder, and manually operable means are provided for so positioning the valve as to 10 enable the hammer to strike a maximum blow or so restricting the escape of air from the cylinder as to cause the hammer to strike a blow of any desirable force less than said maximum.

As illustrated in the drawings the overhead beam is provided in suitable proximity to the exhaust end of the conduit 23 with a vertical cylindrical bore 28 axially crossing the conduit 23 and lined with a cylindrical bushing 29 having diametrically alined ports 30 and 31 coinciding with the conduit 23. The bore 28 is provided at its upper end with a screw threaded wall and a nut 32 which is mounted thereon engages the upper end of the bushing 29. Desirably the nut 32 is provided with a central duct and cavity 25 through which oil may be supplied to the valve with a suitable removable plug closing the duct.

The bore 28 is also provided at its lower end with a screw threaded wall which is engaged by a tubular nut 33 having an integral downwardly 30 projecting extension 34 fitting the cylindrical stem 35 of a cylindrical valve 36 which is rotatably mounted in the bushing 29. The upper face of the nut 33 is provided with an annular countersink containing an antifriction member or 35 packing 37 which surrounds the valve stem 35 and engages the lower face of the valve 36.

The valve 36 is shown in Fig. 6 as a rotatable valve having ports adapted selectively to be positioned to admit air under pressure to the lifting cylinder or to permit controlled exhaust of air from the cylinder. The beam 9 is provided with an inlet passage 38 through which air under pressure is supplied to the valve 36 and thence selectively to proper ports therein to the lifting cylinder to raise the hammer, or through ports 40 in the valve to permit the regulated escape of air from the cylinder. The preferred operating valve 36 has an integral cylindrical head 39 having a diametrical bore 40 therethrough preferably of the same diameter as that of the conduit 23 and provided at its ends with ports 41 and 42 adapted to communicate with the conduit 23 and a radial bore 43 extending at right angles to and communicating with the bore 40, thereby being so positioned that when the valve body is rotated in one, preferably a clockwise direction the valve port 41 will register with the inlet passage 38 and the port 43 with the conduit 23 to admit air under pressure to the lifting cylinder thereby to raise the hammer.

When the valve is rotated in the opposite direction the ports 41 and 42 will both communicate with the conduit 23 to permit escape of air from the lifting cylinder. Manually operable means 65 are provided for rotating the valve in the opposite, counterclockwise, direction so to position the valves 41 in axial alinement with the conduit 23 to permit such rapid exhaust of air from the cylinder as to permit the hammer to drop under the influence of gravity and strike a maximum blow, or selectively to rotate the valve such desired lesser distance that the ports 41 and 42 respectively will be so adjustably positioned as to restrict the rate of exhaust of air from the cylinder to cause a back pressure of the air in the

cylinder in opposition to the force of gravity acting upon the hammer adapted controllably to cause the hammer to strike a blow of any desired force less than said maximum.

Means are provided in the present invention for adjustably limiting the rotative movement of the valves in such manner that repeated blows of the hammer may be struck with uniform force.

Any suitable means may be provided for supplying air under pressure to the inlet port 38 in the overhead beam. In the present construction an elbow fitting 44, such as is usual in the art, is secured to the beam in communication with the inlet port 38 therein and is connected by a preferably flexible pipe 45 to a fitting 46 having a shut-off valve 47 in a conduit 48 leading from an air compressor of the usual type, not shown.

Desirably the flexible pipe 45 is attached to and extends along one of the braces 10 but for clarity of illustration is shown as extending upwardly from the lower fitting 46 to the fitting 44 parallel to the columns 7.

In order to insure accuracy of rotation of the valve 36 and to prevent wear, the valve stem 35 is secured to a vertical actuating rod 49 of a novel universal joint, which is illustrated in Figs. 2 and 9, in which the lower end of the valve stem 35 is provided with a diametrical flat tongue 50 which engages a diametrical groove 51 in a cylindrical member 52 having in its under face a groove 53 extending at right angles to the groove 51. The control rod 49 has at its upper end a tongue 54 adapted to engage the groove 53 (Fig. 9).

A sleeve 55, which is secured to the upper end of the control rod by a bolt 56, surrounds the cylindrical member 52 of the universal joint and the adjoining cylindrical portion 34 of the lower nut 33, thereby preventing lateral displacement of the interengaging members of the universal joint which are held in engagement by the upper and lower bearings of the valve and the controller rod.

The lower end of the valve actuating rod 49 extends axially into a cylindrical socket 58 in the anvil top 4 and desirably is provided at its end with a conical bearing 59 as shown in Fig. 7. The rod 49 has in proximity to the conical end an angular, preferably square, portion 60 adapted to be engaged by downwardly extending members having shoulders adapted to cooperate with stop pins one of which is adjustable to limit the rotation of the valve 36 as hereinafter described. A cylindrical bearing block 61 is mounted in the base of the socket 58 and is adapted to be adjustably secured therein by a set screw 62. It is provided with a central conical socket 63 to receive the conical end 59 of the control rod. A collar 64 having an angular preferably rectangular hole 65 therethrough which fits the rectangular portion 60 of the control rod is mounted upon the upper face of the bearing block 61 and is provided with laterally extending shoulders 66 and 67 as shown in Fig. 7, the shoulder 66 being adapted to engage a stop pin 68 extending upwardly from the bearing block 61 as shown in Figs. 2, 4 and 7. When the valve rod 49 is rotated in a clockwise direction until the shoulder 66 engages the stop pin 68 the port 41 of the valve 36 will communicate with the inlet passage 38 in the beam 9 and the port 43 will communicate with the conduit 23, thereby to supply air under pressure to the lifting cylinder to raise the hammer.

Suitable means are provided for controlling the extent of rotation of the valve actuating rod in a counterclockwise direction so to position the exhaust ports 41 and 42 of the valve in full or restricted communication with the conduit 23, thereby to control the rate of descent of the hammer. The mechanism for accomplishing this purpose comprises a hub 69 which is rotatably mounted upon the lower portion of the valve actuating rod 49 and has a lower cylindrical portion 70 which is rotatably mounted in the cylindrical socket 58 in the top of the anvil. The hub 69 has a downwardly extending pin 71 which is adapted to be engaged by the shoulder 67 of the socket to limit the rotation of the control rod and the valve 36 in a counterclockwise direction. The hub 69 is provided with a laterally extending handle 72 by means of which it may be rotated and is provided therebeneath with an annular groove 73 in which the arcuate end of a clamping plate 74 is seated and which is adapted to be moved to clamping position by a screw 75 having a handle 76 as shown in Figs. 3 and 7. The hub 69 is provided with a scale having graduations 77 adapted to be positioned in registry with an index which, as shown in Figs. 2 and 3, comprises a vertical stud 78 which is mounted in and extends upwardly from the anvil 4 in radial alinement with the stud 68 which projects upwardly from the bearing block 61.

By reason of this construction when the valve-operating rod is rotated in a clockwise direction to cause the shoulder 66 of the collar 64 to engage the stationary pin 68, the port 41 of the valve will register with the inlet port 38 in the overhead beam and the port 43 of the valve will register with the conduit 23 thereby permitting air under pressure to enter the lifting cylinder with full force to raise the piston. By rotative adjustment of the hub in a clockwise direction, the downwardly extending stop pin 71 of the hub 69 may be so positioned that the area of the exhaust ports 41 and 42 of the valve 36 will be positioned so as to restrict the escape of air from the cylinder as to adjust the rate of descent of the hammer to strike a blow of predetermined force. The positioning of the exhaust ports of the valve may be accurately determined by the position of the scale on the hub with respect to the index 78 and the hub fixedly clamped in the desired position to cause the hammer to strike repeated blows with the same predetermined force.

Desirably means are provided to rotate the control rod automatically in a clockwise direction approximately at the time the hammer strikes its blow and thereby to prevent a rebounding blow of the hammer. This is accomplished by usual mechanism comprising a sleeve 79 adjustably mounted upon the control rod above and in proximity to the plane of impact of the hammer upon the anvil and provided with a spiral cam 80 adapted to be engaged by and projected upon the hammer just in advance of the moment of impact.

One of the important features of the invention is to provide a manually operable handle for rotating the control rod in a counterclockwise direction to position the ports 41 and 42 of the valve 36 in communication with the conduit 23 in such manner as to permit the hammer to drop with full force, or to restrict the escape of air from the cylinder in such manner as to control the rate of descent of the hammer and the force of the blow, and which will

not shock the hand of the operator when the control rod is rotated automatically in a clockwise direction by the descending hammer.

In the preferred construction illustrated herein (Figs. 2 and 5) a sleeve 81 is fixedly secured to the control rod 49 at a convenient distance above its base by a pin 82 extending therethrough. The sleeve 81 is provided with a flat face 83 adapted to be engaged by the flat head 84 of a cylindrical plunger 85 which is slidably mounted in a handle 86 and is forced into engagement with the sleeve by a spring 87 in the handle engaging a cylindrical abutment 88 secured within the handle by a screw threaded plug 89 (Fig. 5). The handle 86 has at its end adjacent the control rod a laterally offset arm 90 having a horizontal end portion 91 which is rotatably mounted upon the control rod 49 and secured in position thereupon by a collar 92 engaging the upper face of the arm 91. When, therefore, the control rod is automatically rotated in a clockwise direction upon descent of the hammer the rotation of the sleeve 81 will force the plunger 85 gently out of engagement with the flat face 83 of the collar 81, thus avoiding a shock to the hand of the operator.

Another feature of the drop hammer construction is to provide safety means for preventing improper or unintentional descent of the hammer which might injure the operator or damage the hammer or anvil dies or the blank if therebetween by reason of release or reduction in air pressure in the lifting cylinder caused either by inadvertent operation of the exhaust mechanism or by leakage of air from the lifting cylinder. This is accomplished by providing means for latching the hammer at substantially the upper limit of its movement and also providing a supplemental abutment for preventing the hammer die from striking the anvil die both of which must be manually removed from the path of the hammer by the left hand of the operator before and while the valve controlling rod 49 is operated by the operator's right hand to rotate the valve 36 to exhaust position to permit the hammer to drop. By thus requiring the operator to use both hands after the blank has been placed on the anvil to release and to control the hammer such injuries are impossible.

The mechanism shown in the drawings for preventing such uncontrollable descent of the hammer comprises an abutment rod 93 normally located in the path of the hammer with the lower end of the rod resting upon the flat face of the anvil 4 and its upper end extending above the plane of impact of the hammer and anvil dies. The rod 93 is fixedly secured in a sleeve 94 on the end of an arm 95 extending from a collar 96 which is secured upon a vertical rod 97 which is journaled at its lower end in a suitable bearing in the anvil 4 and is journaled at its upper end in the overhead beam 9 in proximity to and forwardly of the hammer guiding column 6. In order to support the hammer at the upper limit of its movement the rod 97 has fixedly and adjustably secured to it a latch 98 extending in substantial parallelism with the arm 95 of the lower abutment. The latch 98 and the abutment rod 93 are normally held in the path of the hammer by a spiral torsional spring 99 which encircles the upper end portion of the rod 97 and is anchored at its upper end to the overhead beam 9 and at its lower end to a collar which is fixedly secured to the rod 97. The collar 96 is provided with a handle 100 adapted to be

grasped by the left hand of the operator and moved in a clockwise direction to swing the latch 98 and the abutment rod 93 out of the path of the hammer.

In starting the operation of the machine, assuming that the hammer is in raised position with its lower face resting upon the latch 98 and the work placed upon the anvil die, the operator will first grasp the handle 86 with his right hand and rotate it in a clockwise direction thereby positioning the valve ports 41 and 43 respectively in communication with the inlet port 38 and the conduit 23 to supply air under pressure to the lifting cylinder, thereby raising the hammer to the upper limit of its movement and removing the pressure of the hammer upon the latch 98. He will then grasp the handle 100 and rotate the rod 97 in a clockwise direction sufficiently to remove the latch 98 and the abutment rod 93 from the path of the hammer and continue to withhold the latch and abutment out of the path of the hammer. The operator will then rotate the handle 86 of the control rod 49 in a counterclockwise direction to position the ports 41 and 42 in communication with the conduit 23 and if a full blow is to be struck will retain the ports in full registry with the conduit 23. If the operator desires to strike a lesser blow the handle 86 will be rotated such lesser distance as will restrict the rate of exhaust air from the lifting cylinder to such an extent as may be required to strike a blow of predetermined force.

If the operator desires to strike a series of repeated blows of less than full force he will, preparatory to the removal of the latch and abutment from the path of the hammer, grasp the handle 72 of the hub 69 and rotate the hub in a clockwise direction to a position indicated by the registry of a desired graduation of the scale 68 on the hub with the index 78 which extends upwardly from the anvil 4 and will lock the hub in such position by rotation of the clamping screw 75 by its handle 76. The stop pin 71 which extends downwardly from the hub will then be so positioned that when the shoulder 67 on the actuating rod engages the stop pin 71 the registry of the ports 41 and 42 will be so restricted, as illustrated in Fig. 6, as to throttle the escape of air from the lifting cylinder and cause the hammer to strike blows of uniform predetermined force indicated by the setting of the scale upon the hub. By manipulation of the handle 86 of the control rod the hammer may therefore be caused to strike a single blow or repeated blows of uniform predetermined force. As the hammer approaches the plane of impact on each descent the projection thereon will engage the cam 80 and rotate the control rod in a clockwise direction so to position the ports of the valve 36 as to supply air under pressure to the lifting cylinder to raise the hammer.

By reason of engagement of the plunger head 84 of the handle 86 with the flat surface 83 of the collar 81 the automatic rotation of the control rod 49 will merely force the plunger from engagement with the flat surface 83 to engagement with the cylindrical surface of the collar and therefore will not cause any substantial shock to the hand of the operator while grasping the handle 86.

Upon each upward movement of the hammer the collar 26 on the piston 14 of the lifting cylinder will engage the tubular piston rod 21 of the buffer piston 19 and will cushion and arrest the upward movement of the hammer by re-

sistance of the air pressure in the lifting cylinder and the buffer cylinder, as above described.

When it is desired to stop the hammer the operator will release the pressure on the handle 100 of the rod 96 when the hammer approaches the upper limit of its movement and the spring 99 will thereupon swing the latch 98 beneath the lower face or a shoulder of the hammer. If the handle 100 is released at such time during the upward movement of the hammer that the latch may not engage the hammer the abutment rod 83 will be positioned by the spring 99 in the path of the hammer so that the hammer die will be prevented from engaging and injuring the anvil die or the work thereon, or the hands of the operator.

By reason of the communication of the branch 25 of the conduit 23 with the lower portion of the lifting cylinder, as above described, accumulation of excessive oil in the lower portion of the lifting cylinder is discharged by the exhaust of air from the cylinder.

By reason of the universal joint connection between the control rod 49 and the valve 36 wear of the valve 36 and its bearings is practically eliminated.

It will therefore be obvious that by the present invention a drop hammer of simple construction and maximum longevity is provided which may be so controlled as to produce a single blow of full force or any desired lesser force or repeated blows of full force or any desired predetermined lesser force.

It will be understood that the particular mechanisms shown and described herein are of an illustrative character and not restrictive of the meaning and scope of the following claims.

Having thus described the invention, what is claimed as new, and desired to be secured by Letters Patent, is:

1. In a pneumatic drop hammer having an anvil, a frame mounted thereon having vertical columns for guiding the hammer connected at their upper end by an overhead beam, a hammer reciprocably mounted on said columns, and a cylinder mounted on said beam having a piston connected to the hammer, a conduit in said beam communicating at one end with the cylinder and at its other end with the atmosphere, a rotatable valve in said conduit having ports adapted respectively to be positioned to admit air into the cylinder or to permit escape of air from the cylinder and the hammer to drop, and means for supplying air under pressure to said valve, the provision of valve actuating mechanism comprising a rotatable vertical rod connected to and in axial alignment with said valve, and journaled at its lower end in said anvil, means rigid with the lower end of said rod having shoulders extending outwardly therefrom in different directions, a stop member rigid with said anvil positioned to engage one of said shoulders when the rod is rotated in a direction to position the valve ports to admit air into the cylinder, and a stop member adjustably mounted on said anvil adapted to be positioned in the path of the other shoulder so to limit the rotation of the rod as to cause the ports of the valve so to restrict the escape of air from the cylinder as to cause the hammer to strike a blow of predetermined force.

2. In a pneumatic drop hammer having an anvil, a frame mounted thereon having vertical columns for guiding the hammer connected at their upper end by an overhead beam, a hammer

reciprocably mounted on said columns, and a cylinder mounted on said beam having a piston connected to the hammer, a conduit in said beam communicating at one end with the cylinder and at its other end with the atmosphere, a valve in said conduit having ports adapted respectively to be positioned to admit air into the cylinder or to permit escape of air from the cylinder and the hammer to drop, and means for supplying air under pressure to said valve, the provision of valve actuating mechanism comprising a rotatable vertical rod connected to and in axial alignment with said valve and journaled at its lower end in said anvil, means rigid with the lower end of said rod having shoulders extending outwardly therefrom in different directions, a stop member rigid with said anvil positioned to engage one of said shoulders when the rod is rotated in a direction to position the valve ports to admit air into the cylinder, and a stop member adjustably mounted on said anvil adapted to be positioned in the path of the other shoulder so to limit the rotation of the rod as to cause the ports of the valve so to restrict the escape of air from the cylinder as to cause the hammer to strike a blow of predetermined force, and means for securing the adjustable stop member in adjusted positions thereby to cause the hammer to strike repeated blows of the same predetermined force.

3. In a pneumatic drop hammer having an anvil, a frame mounted thereon having vertical columns for guiding the hammer connected at their upper end by an overhead beam, a hammer reciprocably mounted on said columns, and a cylinder mounted on said beam having a piston connected to the hammer, a conduit in said beam communicating at one end with the cylinder and at its other end with the atmosphere, a valve in said conduit having ports adapted respectively to be positioned to admit air into the cylinder or to permit escape of air from the cylinder and the hammer to drop, and means for supplying air under pressure to said valve, the provision of valve actuating mechanism comprising a rotatable vertical rod connected to and in axial alignment with said valve, a bearing for the lower end of said rod mounted in said anvil and having a stop extending upwardly therefrom, means fixedly secured to the lower end portion of said rod engaging said bearing member and having laterally extending arms one of which is adapted to engage said stop when said rod is rotated to position the valve ports to admit air into the cylinder, a manually operable control member rotatably mounted upon said rod having a downwardly extending stop adapted to be engaged by the other arm on said rod to limit the rotative movement of said rod in the opposite direction thereby to position the exhaust ports of said valve so to restrict the escape of air from the cylinder to cause the hammer to strike a blow of predetermined force, and means for locking said control member in adjusted positions to cause the hammer to strike repeated blows of the same predetermined force.

4. In a pneumatic drop hammer having an anvil, a die-supporting anvil, a frame mounted on said anvil having vertical columns for guiding the hammer connected at their upper ends by an overhead beam, a hammer reciprocably mounted on said columns, a lifting cylinder mounted on said beam having a piston connected to the hammer, a conduit in said beam communicating at one end with said cylinder and at its other end with the atmosphere, a vertical

cylindrical socket in the anvil, a vertical three-way valve rotatably mounted in said beam in axial alinement with the socket in said anvil and having inlet and exhaust ports adapted selectively to communicate with said conduit and to be positioned to supply air to the cylinder or to permit the exhaust of air therefrom, and means for supplying air under pressure to said valve, the provision of means for actuating said valve comprising a rod connected to said valve and extending into said socket having at its end a portion forming a journal, a bearing member therefor fixedly secured in said socket having an upwardly projecting stationary stop, a rotatably adjustable hub mounted in said socket having a complementary downwardly projecting stop, means fixedly secured to said rod between said bearing and said hub having shoulders extending therefrom in different predetermined directions, one of said shoulders being adapted upon rotation of the control rod in one direction to engage the fixed stop and thereby position the inlet ports of said valve to supply air to the cylinder and the other of which shoulders is adapted upon rotation of said rod in the opposite direction to engage the stop of the adjustable hub and so position the exhaust ports of the valve as to regulate the rate of exhaust of air from the cylinder and thereby control the force of blow of the hammer.

5. In a pneumatic drop hammer having an anvil, a die-supporting anvil, a frame mounted on said anvil having vertical columns for guiding the hammer connected at their upper ends by an overhead beam, a hammer reciprocably mounted on said columns, a lifting cylinder mounted on said beam having a piston connected to the hammer, a conduit in said beam communicating at one end with said cylinder and at its other end with the atmosphere, a vertical cylindrical socket in the anvil, a vertical three-way valve rotatably mounted in said beam in axial alinement with the socket in said anvil and having inlet and exhaust ports adapted selectively to communicate with said conduit and to be positioned to supply air to the cylinder or to permit the exhaust of air therefrom, and means for supplying air under pressure to said valve, the provision of means for actuating said valve comprising a rod connected to said valve and extending into said socket having in proximity to its end an angular section terminating in a conical end portion forming a journal, a bearing member therefor rotatably and adjustably mounted in said socket having a conical bearing for the end of said rod secured in said socket having an upwardly projecting stationary stop pin, a rotatably adjustable hub mounted in said socket having a complementary downwardly projecting stop pin, a collar mounted on the angular section of said shaft having shoulders extending therefrom in different predetermined directions, one of said shoulders being adapted upon rotation of the control rod in one direction to engage the fixed stop and thereby position the inlet ports of said valve to supply air to the cylinder and the other of which shoulders is adapted upon rotation of said rod in the opposite direction to engage the stop of the adjustable hub and so position the exhaust ports of the valve as to regulate the rate of exhaust of air from the cylinder and thereby control the force of blow of the hammer.

6. In a pneumatic drop hammer having an anvil, a die-supporting anvil, a frame mounted on said base having vertical columns for guiding the

hammer connected at their upper ends by an overhead beam, a hammer reciprocably mounted on said columns, a lifting cylinder mounted on said beam having a piston connected to the hammer, a conduit in said beam communicating at one end with said cylinder and at its other end with the atmosphere, a vertical cylindrical socket in the anvil, a vertical three-way valve rotatably mounted in said beam in axial alinement with the socket in said anvil and having inlet and exhaust ports adapted selectively to communicate with said conduit and to be positioned to supply air to the cylinder or to permit the exhaust of air therefrom, and means for supplying air under pressure to said valve, the provision of means for actuating said valve comprising a rod connected to said valve and extending into said socket having at its end a portion forming a journal, a bearing member therefor fixedly secured in said socket having an upwardly projecting stationary stop, a rotatably adjustable hub mounted in said socket having a complementary downwardly projecting stop, means fixedly secured to said rod between said bearing and said hub having shoulders extending therefrom in different predetermined directions, one of said shoulders being adapted upon rotation of the control rod in one direction to engage the fixed stop and thereby position the inlet ports of said valve to supply air to the cylinder and the other of which shoulders is adapted upon rotation of said rod in the opposite direction to engage the stop of the adjustable hub and so position the exhaust ports of the valve as to regulate the rate of exhaust of air from the cylinder and thereby control the force of blow of the hammer, an index member mounted in said anvil support radially opposite to the fixed stop member, a scale on said hub cooperating with said index member adapted upon rotation of said hub to indicate the position of the exhaust ports of the valve, and means for clamping the hub member in adjusted position as indicated by the scale to determine the rate of exhaust of air from the cylinder and the predetermined force of repeated blows of the hammer.

7. In a pneumatic drop hammer having an anvil, a frame mounted thereon having vertical columns for guiding the hammer connected at their upper end by an overhead beam, a hammer reciprocably mounted on said columns, and a cylinder mounted on said beam having a piston connected to the hammer, a conduit in said beam communicating at one end with the cylinder and at its other end with the atmosphere, a rotatable valve in said conduit having ports adapted respectively to be positioned to admit air into the cylinder or to permit escape of air from the cylinder and the hammer to drop, and means for supplying air under pressure to said valve, the provision of valve actuating mechanism comprising a rotatable vertical cylindrical rod connected to and in axial alinement with said valve and journaled at its lower end in said anvil and having in proximity thereto a flat surface, cooperating means on said hammer and rod operable when the hammer closely approaches the anvil automatically to rotate the valve in a direction to admit air to the cylinder, an operating handle rotatably mounted on said rod having means releasably engaging said rod with sufficient force to enable the rotation thereof adjustably to place the ports of the valve in predetermined exhaust position and to release such engagement when the rod is automatically rotated in the opposite direction by the dropping hammer, thereby

avoid shock to the hand and arm of the operator.

8. In a pneumatic drop hammer having an anvil, a frame mounted thereon having vertical columns for guiding the hammer connected at their upper end by an overhead beam, a hammer reciprocably mounted on said columns, and a cylinder mounted on said beam having a piston connected to the hammer, a conduit in said beam communicating at one end with the cylinder and at its other end with the atmosphere, a rotatable valve in said conduit having ports adapted respectively to be positioned to admit air into the cylinder or to permit escape of air from the cylinder and the hammer to drop, and means for supplying air under pressure to said valve, the provision of valve actuating mechanism comprising a rotatable vertical cylindrical rod connected to and in axial alignment with said valve and journaled at its lower end in said anvil and having in proximity thereto cooperating means on said hammer and rod operable when the hammer closely approaches the anvil automatically to rotate the valve in a direction to admit air to the cylinder, an operating handle rotatably mounted on said rod having a spring pressed plunger mounted thereon and movable longitudinally thereof, a flat head engaging the flat surface on said rod operable to rotate the rod in a direction adjustably to place the ports of 25 said valve in predetermined exhaust position and operable upon automatic rotation of the rod in the opposite direction by the dropping of the hammer to avoid shock to the hand and arm of the operator.

9. In a pneumatic drop hammer of that type having an anvil, a hammer-guiding frame with an overhead beam, vertically aligned lifting and buffer cylinders on the beam, a piston for the lifting cylinder having a piston rod connected 40

to the hammer, and a piston for the buffer cylinder having a tubular stem slidably mounted on the piston rod, the provision of an annular plate mounted on the beam forming a common head for the lifting and buffer cylinders and provided with means for permitting air to pass from the lifting cylinder to the buffer cylinder, and a valve-controlled means for selectively supplying air under pressure to the lifting cylinder to raise the hammer and thence to the buffer cylinder to cushion and arrest the hammer at the upper limit of its movement.

10. In a pneumatic drop hammer the construction as defined in claim 9 in which the said annular plate has an upwardly extending inner wall narrowly spaced from the piston rod acting to secure the discharge of oil accumulated between the said inner wall and the internal periphery of the lifting cylinder when the air is exhausted from the lifting cylinder.
